DESIGN FOR A HAT

Joy I. McKie, Salina, Kans.

Application April 7, 1947, Serial No. 138,196

Term of patent 14 years

(Cl. D3—13)

To all whom it may concern:

Be it known that I, Joy I. McKie, a citizen of the United States, residing at 607 N. 10th Street, Salina, Kansas, have invented a new, original, and ornamental Design for a Hat, of which the following is a specification, reference being had to the accompanying drawing, forming a part thereof.

Fig. 1 is a perspective view from one side; Fig. 2 is a perspective view between the front and side; and Fig. 3 is a perspective view from the front of a hat embodying my new design.

The hat is reversible, and Figures 1 and 3 show it in one position while Fig. 2 shows the same reversed or turned inside out.

I claim:

The ornamental design for a hat, as shown and described.

JOY I. MCKIE.
